UNITED STATES PATENT OFFICE.

PERRY C. GALLAWAY, OF ABBOTT, TEXAS.

DESIGN FOR A REIN-HOLDER.

SPECIFICATION forming part of Design No. 29,266, dated August 23, 1898.

Application filed July 30, 1898. Serial No. 687,366. Term of patent 14 years.

To all whom it may concern:

Be it known that I, PERRY C. GALLAWAY, a citizen of the United States, residing at Abbott, in the county of Hill and State of Texas, have invented and produced a new and original Design for a Rein-Holder, of which the following is a specification.

This invention relates to a new and original design for a rein-holder; and it has for its object to provide a design of this character that shall be both useful and ornamental.

The leading feature of the design resides in an arched or bowed body of an approximate **U** form and provided at the top thereof with a central crest-piece, having a pair of reversely-arranged abutting ring scrolls extended at their upper sides into an inverted-V-shaped figure.

The minor features of the design are the arched or bowed body having sigmoidally-curved legs and elongated **S**-scroll braces arranged at opposite sides of the central crest-piece and connected at their opposite ends, respectively, with the ring scrolls and the top portion of the body.

In the drawing the figure is an elevation or front view of a rein-holder embodying the herein-described design.

Referring to the drawing, the numeral 1

designates the arched or bowed body or support of the holder, and this body or support is provided with sigmoidally-curved pendent legs 2. By reason of the pendent legs 2 and the arched or bowed form of the body the latter is necessarily of an approximately **U** shape, and at the top thereof said body is provided with a central crest-piece 3, having a pair of reversely-arranged abutting ring scrolls 4, the upper outer terminals of which ring scrolls are joined together and extended upward to form an inverted-V-shaped figure 5. At opposite sides of the central crest-piece 3 are arranged the oppositely-located elongated **S**-scroll braces 6, which are connected at their opposite ends, respectively, with the ring scrolls 4 and the top portion of the body or support 1.

What is claimed is—

The design for a rein-holder herein shown and described.

In testimony that I claim the foregoing as my own I have hereto affixed my signature in the presence of two witnesses.

PERRY C. GALLAWAY.
